US00D820142S

(12) **United States Design Patent** (10) **Patent No.:** **US D820,142 S**
(45) **Date of Patent:** **** Jun. 12, 2018**

(54) **NECKLACE**

(71) Applicant: **ACE LIGHT & ELECTRONIC TECH(NINGBO) CO., LTD.**, Ningbo, Zhejiang Province (CN)

(72) Inventor: **Yanbei Qin**, Ningbo (CN)

(73) Assignee: **ACE LIGHT & ELECTRONIC TECH(NINGBO) CO., LTD.**, Ningbo (CN)

(**) Term: **15 Years**

(21) Appl. No.: **29/597,686**

(22) Filed: **Mar. 19, 2017**

(30) **Foreign Application Priority Data**

Sep. 23, 2016 (CN) 2016 3 0479464
